UNITED STATES PATENT OFFICE.

WILLIAM WHARTON, JR., OF PHILADELPHIA, PENNSYLVANIA, ASSIGNOR
TO THE WILLIAM WHARTON, JR., & COMPANY, INCORPORATED, OF
SAME PLACE.

SPRING-BOX FOR FROGS, SWITCHES, &c.

SPECIFICATION forming part of Letters Patent No. 654,039, dated July 17, 1900.

Application filed May 31, 1900. Serial No. 18,576. (No model.)

To all whom it may concern:

Be it known that I, WILLIAM WHARTON, Jr., a citizen of the United States, residing in Philadelphia, Pennsylvania, have invented 5 certain Improvements in Spring-Boxes for Frogs, Switches, &c., of which the following is a specification.

My invention relates to certain improvements in spring-boxes for railway switches, 10 frogs, &c., being a companion application to that filed by Warner B. Cooke November 18, 1899, Serial No. 737,513; and the object of my invention is to simplify the construction of the box, as fully described hereinafter.

15 In the accompanying drawings, Figure 1 is a plan view of a frog, illustrating my invention. Fig. 2 is a sectional view on the line 2 2, Fig. 1. Fig. 3 is a section on the line 3 3, Fig. 2. Figs. 4, 5, and 6 are perspective views illustrating details of my invention. Fig. 7 is a view of the box-blank before being 20 bent, and Fig. 8 is a view of a modification of the box.

Spring-boxes are used in connection with 25 railway switches and frogs to keep the movable rail pressed firmly against the fixed rail, while allowing the movable rail to yield when forced over by the flange of a car-wheel passing between the fixed rail and the movable 30 rail.

A' are fixed rails, A being the main rail, and A' the rail of a siding or turnout, which has a fixed relation to the rail A.

A³ is the fixed wing-rail of the frog, and A³ 35 is the movable wing-rail. While I have shown a frog construction in this instance, it will be understood that my invention may be used in connection with ordinary spring switch-rails and in other places where it is 40 desirable to hold a movable rail in yielding contact with the fixed rail.

B is the spring-box, and D is the base-plate, upon which the spring-box is mounted. This plate extends under the rails A A' A² A³ and 45 is secured to the rails A A' A², and the base-plate forms a suitable support upon which the rail A³ can slide. The box B is made from a blank, as clearly shown in Fig. 7, having a rear extension b. When the box is bent 50 to a suitable form, as shown in Fig. 4, the

central portion b' forms the top of the box, the portions b² at each side form the sides of the box, and the extensions b³ form the flanges by which the box is secured to the base-plate. The rear extension b is turned down to form 55 the rear end of the box and has a flange b⁴ turned out, which extends under the lip d on the base-plate D. Bolts c or other suitable fastenings are used to secure the box to the base-plate, and the central holes at each side 60 receive the spikes which secure the structure to the tie. An adjusting-screw E is mounted on the back plate b of the box and has a collar on the inner side and is headed, so that it can be turned by a wrench.

65 F is a square washer or plate adapted to the box and has a threaded opening through which passes the screw E.

G, Figs. 2 and 5, is a sliding plate bent at an angle, as shown, and having a projecting 70 pin g. Mounted between this plate and the washer F are one or more springs I. I have shown two in the present instance; but a single spring may be used, if desired. The pin g and the screw E support the springs.

75 Secured to the side of the rail A³ is a T-shaped plate H, bent as clearly shown in Fig. 6, forming a projection h, rounded at the end and adapted to bear against the vertical portion of the slide G. The wings h' of the T- 80 shaped plate H are secured to the web of the rail by bolts or other fastenings.

It will be seen by the above description that the spring-box is so situated as to keep the rail A³ normally in contact with the fixed rail 85 A'; but when a car-wheel traverses the rail A' its flange will force the movable rail A³ away from the rail A' and will compress the springs I in the spring-box B. As soon as the flange of the wheel has passed through 90 the opening thus made the rail A³ will be immediately forced back to its normal position by the springs.

By making the spring-box with a depending portion at the rear, extending in front of 95 a lip on the base-plate, the thrust is taken up by the end of the box itself and all intermediate devices are dispensed with, and where the rear extension has a flange b⁴, over which extends a lip d, the rear portion of the box is 100

held down upon the base-plate without other fastenings. In some instances, however, I may make the box as shown in the modification, Fig. 8, in which the flange b^4 is dispensed with and a lip is simply turned up on the base-plate.

I claim as my invention—

1. The combination in a spring-box for frogs, switches, &c., of a base-plate and a plate bent to form the top, the rear and the sides of a box, and means for securing the said box to the plate, substantially as described.

2. The combination in a spring-box for frogs, switches, &c., of a base-plate, and a plate bent to form the top, the two sides with their flanges and the rear of the box, said base-plate having a vertical lip at the rear overlapping the rear plate of the box, substantially as described.

3. The combination in a spring-box for frogs, switches, &c., of a base-plate secured to the fixed rails, a movable rail adapted to

slide on the base-plate, a spring-box bent up from sheet metal so as to form the top, the 25 sides and the rear of the box, the rear portion having a flange, a lip on the base-plate overlapping the said flange, a spring within the box, and a projection on the movable rail to bear against the spring, substantially as described.

4. The combination of a base-plate having an overlapping lip at its rear end, and a spring-box made of sheet metal having its rear end formed by bending down the metal 35 from the blank, a flange being formed on the rear end of the box and extending under the lip on the base-plate, substantially as described.

In testimony whereof I have signed my 40 name to this specification in the presence of two subscribing witnesses.

WILLIAM WHARTON, JR.
